(57) CLAIM

The ornamental design for a match holder, as shown and described.

DESCRIPTION

FIG. 1 is a perspective view of a match holder, illustrating our new design in a configuration of use;

FIG. 2 is a perspective view;

FIG. 3 is a left elevational view;

FIG. 4 is a right elevational view;

FIG. 5 is a front elevational view;

FIG. 6 is a rear elevational view;

FIG. 7 is a top plan view; and,

FIG. 8 is a bottom plan view.

The matches illustrated in broken lines in FIG. 1 are environmental structure that forms no part of the claimed design. All other broken lines in the drawing figures indicate portions of the match holder that form no part of the claimed design.
